(57) **CLAIM**

The ornamental design for a flush ceiling exhaust fan shield as shown and described.

DESCRIPTION

FIG. 1 is a top, right front axonometric view of a flush ceiling exhaust fan shield showing my new design in the environment of use.

FIG. 2 is a bottom, right rear axonometric view of the thereof.

FIG. 3 is a front elevational view thereof, the rear elevational view being a mirror image of the front elevational view.

FIG. 4 is a left side elevational view thereof, the right side elevational view being a mirror image of the left side elevational view.

FIG. 5 is a top plan view thereof.

FIG. 6 is a bottom plan view thereof.

FIG. 7 is a top, right front axonometric view of the flush ceiling exhaust fan shield of FIG. 1;

FIG. 8 is a bottom, right rear axonometric view of the thereof.

FIG. 9 is a front elevational view thereof, the rear elevational view being a mirror image of the front elevational view.

FIG. 10 is a left side elevational view thereof, the right side elevational view being a mirror image of the left side elevational view.

FIG. 11 is a top plan view thereof; and,

FIG. 12 is a bottom plan view thereof.

Broken lines illustrate portions of the flush ceiling exhaust fan shield that form no part of the claimed design. Additional broken lines in FIGS. 1-6 illustrate environment and form no part of the claimed design.

1 Claim, 10 Drawing Sheets
